UNITED STATES PATENT OFFICE.

JAMES H. LEWIS, OF DETROIT, MICHIGAN.

ROAD-CART.

SPECIFICATION forming part of Letters Patent No. 428,921, dated May 27, 1890.

Application filed January 31, 1890. Serial No. 338,821. (No model.)

To all whom it may concern:

Be it known that I, JAMES H. LEWIS, a citizen of the United States, residing at Detroit, in the county of Wayne and State of Michigan, have invented certain new and useful Improvements in Road-Carts, of which the following is a specification, reference being had therein to the accompanying drawings.

This invention relates to new and useful improvements in road-carts; and the invention consists in the peculiar construction of the seat and seat-support, whereby the horse motion is dispensed with and a more comfortable and efficient device is made, as hereinafter more fully described.

In the drawings which accompany this specification, Figure 1 is a rear elevation of my improved cart. Fig. 2 is a vertical central longitudinal section thereof. Fig. 3 is an enlarged cross-section on line $x-x$ in Fig. 2. Fig. 4 is a detached perspective view of the bearing for the seat.

A are the wheels. B are the shafts. C is the axle. D is the cross-bar. E is the semi-elliptic spring which is clipped to the axle. These parts are of well-known and usual construction.

F is the seat, which is pivotally supported upon the spring E by means of the U-shaped seat-supporting bracket G, secured at its upper ends to the seat and at its lower bent portion pivotally secured to the block H beneath the caps H', clipped upon the spring E, there being an intermediate block I between the block H and the spring. The seat is provided at each side with the side pieces J, which on their lower edge are preferably cut into segmental circular shape, as at K, which moves over the corresponding segmental face L, formed upon the block M at the rear end of the seat-bar N, which bars are pivotally connected at their forward ends to the cross-bar D. The block M is provided with a downwardly-projecting ear a, pivotally connected to the supporting-arms b, which at their lower ends are secured to the block I upon the spring.

c are spring-plates secured on the inner side of the blocks M, and preferably of segmental circular shape, having the ears or lugs d projecting inwardly at their ends. To these

lugs are preferably secured the rod e, which passes through a suitable aperture in the bracket G, and over which are sleeved the spiral springs f—one on either side of the bracket G—bearing with one end against the bracket and at the other end against the lugs d. This bracket is made adjustable upon the block M by means of the bolts g, engaging into the slots h. This adjustment does not change the tension of the springs upon the seat-supporting bracket D, but simply changes the angle at which the seat will normally stand in relation to the spring.

O is a foot rest or crate, which consists of the usual curved bars secured at their rear ends to the under side of the seat, connected together by slats. At their forward ends I preferably leave them free, or I may connect them by a strap P to the cross-bar to prevent their being depressed too far when the driver steps in or out, when his whole weight is sustained thereby. This strap is made adjustable, so that it may be lengthened or shortened to suit the convenience of the driver.

In practice, when the driver occupies the seat, as it is not rigidly connected in any way with the shaft, the horse motion in the shafts and the seat-bars is communicated to the seat only through the medium of the springs f, and the weight of the rider acting against the springs checks any oscillation of the seat.

The horse motion which is transmitted to the rider through the seat-bars in previous constructions has no effect in my cart, as the seat-bars have no connection with the shafts or cross-bars.

What I claim as my invention is—

1. In a road-cart, the combination, with the seat and the seat-supporting spring, of an oscillating seat-supporting frame mounted upon said spring, and of check-springs applied to said frame to counteract the oscillation thereof, substantially as described.

2. In a road-cart, the combination, with a seat mounted on oscillating supports to have a free play in the longitudinal direction of the cart, of check-springs applied thereto to counteract the oscillations, and of seat-bars supported independently of the seat and holding such check-springs in position, substantially as described.

3. In a road-cart, the combination, with a supporting-frame pivotally mounted upon a seat-supporting spring and carrying the seat free to oscillate in the longitudinal direction of the cart, of check-springs on opposite sides of the seat and engaging with the oscillating supports to check their motion, substantially as described.
4. In a road-cart, the combination, with the seat and the seat-supporting spring, of an oscillating seat-supporting frame mounted upon said spring, of check-spring applied to said frame, and of adjusting devices for said spring, substantially as described.
5. In a road-cart, the combination, with the seat and the seat-supporting spring, of the supports G, interposed between and pivotally supported upon said spring, the check-springs, which hold said supports in position, the independent seat-bars, to which said check-springs are secured, and the supporting-frame under the rear end of said seat-bars, substantially as described.
6. In a road-cart, the combination of the seat-supporting springs, the oscillating seat-supports pivotally supported thereon, the
- check-springs, which hold it in position, the independent seat-bars, to which said springs are secured, and the circular bearings between such seat and seat-bars, substantially as described.
7. In a road-cart, the combination, with the springs, of the U-shaped seat-supports G, the seat-bars hinged at their forward ends, the standards b, pivotally supporting the rear end of the seat-bars, the segmental circular faces K and L, and the check-springs f, sleeved upon the rod e, substantially as described.
8. In a road-cart, the combination, with an oscillating seat-frame mounted upon the seat-supporting springs, of check-springs to counteract the oscillations of said frame, and of the foot-rest secured only to said seat, substantially as described.

In testimony whereof I affix my signature, in presence of two witnesses, this 10th day of December, 1889.

JAMES H. LEWIS.
